DESIGN.

—o—
R. W. BINNS.
EWER OR JUG.

No. 20,064.

Patented July 29, 1890.

UNITED STATES PATENT OFFICE.

RICHARD WILLM. BINNS, OF WORCESTER, COUNTY OF WORCESTER,
ENGLAND.

DESIGN FOR A EWER OR JUG.

SPECIFICATION forming part of Design No. 20,061, dated July 29, 1890.

Application filed April 21, 1890. Serial No. 348,922. Term of patent 7 years.

To all whom it may concern:

Be it known that I, RICHARD WILLIAM BINNS, director of the Royal Porcelain Works, Worcester, a subject of the Queen of Great Britain, residing at Worcester, in the county of Worcester, in the Kingdom of Great Britain, have invented and produced a new and original Design for a Ewer or Jug, of which the following is a specification, reference being had to the accompanying photograph, forming a part thereof.

The leading features of this are: the conical body with floral beading round the body, the upper portion of body and mouth with double imitation joints at intervals to represent a vine-stem with branches and star-like leaves joining the neck, and a short thick imitation jointed stump projecting from the side where the handle joins. The general transverse section of the body is round.

What I claim is—

The design for a ewer or jug herein shown and described, the same comprising a conical body, an ornamented beading round the base thereof, a handle formed as a distorted vine-stem joining the neck of the jug, with divided branches and leaves, a neck curved over and with the appearance of double joints at intervals and projecting from the base of the neck in imitation of the said vine, and an imitation stump of the same plant where the handle joins to the neck at an angle.

In testimony whereof I have signed my name to this specification in the presence of two subscribing witnesses.

RICH. WILLM. BINNS.
